DESIGN FOR A COMBINED LIQUID CIGARETTE EXTINGUISHER AND ASH TRAY

Walter Mazen and Lewis Lee Nagle,
Detroit, Mich.

Application September 29, 1944, Serial No. 115,822

Term of patent 7 years

(Cl. D85—2)

To all whom it may concern:

Be it known that we, Lewis L. Nagle and Walter Mazen, citizens of The United States, residing at Detroit, in the county of Wayne and State of Michigan, have invented a new, original, and ornamental Design for a Combined Liquid Cigarette Extinguisher and Ash Tray, of which the following is a specification, reference being had therein to the accompanying drawing forming a part thereof, in which

Figure 1 is a top plan view of a combined liquid

cigarette extinguisher and ash tray showing our new design.

Figure 2 is a view in side elevation.

Figure 3 is a longitudinal, vertical, central sectional view.

We claim:

The ornamental design for a combined liquid cigarette extinguisher and ash tray, as shown and described.
